UNITED STATES PATENT OFFICE.

JAMES H. PARK, OF BURLINGTON, NEW JERSEY, AND BYERLY HART, OF PHILADELPHIA, PENNSYLVANIA.

DESIGN FOR AN OIL-CLOTH PATTERN.

Specification forming part of Design No. 5,727, dated March 26, 1872.

To all whom it may concern:

Be it known that we, JAMES H. PARK, of Burlington, county of Burlington, State of New Jersey, and BYERLY HART, of city and county of Philadelphia and State of Pennsylvania, have invented a new and useful Design for Oil-Cloths; and we do hereby declare the following to be descriptive thereof, reference being had to the accompanying photographic illustration, which fully represents our design.

We claim—

The design for oil-cloths, as shown. To the above we have signed our names this 19th day of January, 1872.

JAMES H. PARK.
BYERLY HART.
